ATTORNEY

UNITED STATES PATENT OFFICE.

SAMUEL C. BEAMER, OF MARSHALLTOWN, IOWA.

EGG-TURNING TRAY.

1,306,164.

Specification of Letters Patent. Patented June 10, 1919.

Application filed June 15, 1917. Serial No. 174,965.

To all whom it may concern:

Be it known that I, SAMUEL C. BEAMER, a citizen of the United States, residing at Marshalltown, in the county of Marshall and 5 State of Iowa, have invented certain new and useful Improvements in Egg-Turning Trays, of which the following is a specification.

This invention relates to egg turning trays 10 and the primary object is to provide a device to be used in incubators or the like and constructed to permit the eggs to be turned evenly and without danger of injury.

The invention also aims to provide a tray 15 of this character which will cause the eggs to be turned by virtue of frictional engagement with the eggs and with each other during movement of the tray.

A further object of this invention is the 20 provision of an egg turning tray which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, 30 wherein is illustrated the preferred form of my invention, in which;

Figure 1 is a top plan view.

Fig. 2 is a section on the line 2—2 of Fig. 1, and

35 Fig. 3 is a section on the line 3—3 of Fig. 1.

Referring to the drawing, wherein is illustrated the preferred form of my invention, and in which like numerals of reference indicate corresponding parts throughout the several views, a retaining cabinet or casing 1 is provided and consists of the front and rear walls 2 and 3 and the end walls 4. Each end wall is provided at its bottom edge with a 45 strip 5 which extends inwardly and forms a ledge 6. Slidably mounted upon the ledge 6 is a tray 7 which includes a rectangular frame of an area considerably greater than the area of the cabinet 1. For the purpose 50 of permitting slidable movement on the frame on the ledge, the front and rear walls 2 and 3 are provided with elongated openings 8 so that the frame may project from

either side of the cabinet. For completing the tray, the frame receives the marginal 55 edge of a rectangular panel of screen or other suitable foraminous material.

The eggs, of course, will be placed on the tray within the cabinet 1 and one side of the tray will be extended beyond the cabinet 60 and exposed at the exterior thereof as shown in full lines in Figs. 1 and 2 of the drawing. The openings 8 are less in width than the diameter of the eggs and it will be apparent that when the tray is slowly thrust inwardly, 65 the eggs within the cabinet will be turned by virtue of the frictional engagement of the eggs with the screen and with each other. If this movement is accomplished slowly over as desired and the tray will be projected from the opposite side of the cabinet 70 as shown by dotted lines of Figs. 1 and 2 of the drawing.

The tray may be quickly removed by simply sliding it off the ledges but when in operative position, sliding movement may be limited by a pair of pivotally mounted nuts 9 which may be swung to horizontal position for permitting withdrawal of the tray 80 from the cabinet. The cabinet may be mounted in any suitable manner within the incubator.

From the foregoing it will be observed that a very simple and durable egg turning 85 tray has been provided, the details of which embody the preferred form. I desire it to be understood, however, that slight changes in the minor details of construction may be made without departing from the spirit of 90 the invention or the scope of the claim hereunto appended.

I claim—

An egg turning tray adapted to receive a plurality of eggs assembled together in the 95 tray and having their surfaces in contact, comprising a cabinet having longitudinal openings formed in its opposite side walls, a movable tray including side and end portions provided with a foraminous bottom attached to the said side and end portions and of an area greater than the area of the said cabinet, the said tray being adapted for reception in the openings to extend beyond the 100 sides of the cabinet, the said foraminous bottom supporting the eggs and presenting a 105

roughened surface whereby turning movement is imparted to the eggs when the said tray is slid through the said openings in the sides of the cabinet, the said relatively rough 5 surface presented by the foraminous bottom as compared with the comparatively smooth surface of the eggs within the tray, permitting the said eggs to make a partial turn

while the said tray is being slid through the cabinet.

In testimony whereof I affix my signature in presence of two witnesses.

SAMUEL C. BEAMER.

Witnesses:

FRED HOES,

J. H. BEAMER.
